UNITED STATES PATENT OFFICE.

CHARLES N. LEONARD, OF INDIANAPOLIS, INDIANA, ASSIGNOR TO THE DRAKE & WOOD COMPANY, OF SAME PLACE.

PORTFOLIO.

SPECIFICATION forming part of Letters Patent No. 471,390, dated March 22, 1892.

Application filed March 17, 1891. Serial No. 385,363. (No model.)

To all whom it may concern:

Be it known that I, CHARLES N. LEONARD, a citizen of the United States, residing at Indianapolis, in the county of Marion and State 5 of Indiana, have invented certain new and useful Improvements in Portfolios, of which the following is a specification.

My said invention relates to an improved construction in portfolios for receiving music, papers, drawings, pictures, and such like articles, which are usually in sheet form, whereby the sheets may be held in a flat and smooth condition when stowed therein whether a few sheets be contained in the 15 portfolio or many, which construction provides easy and convenient access to the receptacle when desired and means by which it may be kept closed when not in use, the top of said portfolio being also so formed as 20 to serve as a center-table or stand, thus adapting the article for a double use, while occupying only such space as is usually occupied by a stand or center-table alone, all as will be hereinafter more particularly described and 25 claimed.

Referring to the accompanying drawings, which are made a part hereof, and on which similar letters of reference indicate similar parts, Figure 1 is a perspective view of one 30 of my improved portfolios, the receptacle being shown tilted to one side to permit access thereto; Fig. 2, a cross-section showing the receptacle in the closed position; Fig. 3, a detail perspective view of one of the hinged partitions of the receptacle; and Fig. 4, a view 35 similar to Fig. 2, illustrating a modified construction.

In said drawings, the portions marked A represent the frame-work or stand, and B the 40 receptacle.

The stand A is not dissimilar in construction from many stands or center-tables in common use, the ends being so formed either by arranging the legs in the form of a cross, 45 as shown in the drawings, or in any other suitable manner to afford a bearing for the pivots or hinges upon which the receptacle is mounted. It will be understood, of course, that said frame or stand may be constructed 50 in any manner desired and used as an ornamental center-table, card-table, book-rack, or

any other article to the use of which it can be adapted.

The receptacle B is trough-shaped, preferably narrow at its bottom and wide at its top, 55 its top width being just sufficient so that its top edges will register with the lower edges of the side pieces of the frame which supports the table-top. It is mounted between the ends of the stand on pivots or hinges b, 60 said pivots being provided with suitable bearings in each end of the frame-work, as shown. On each side is provided a spring-latch b', adapted to engage with a catch a on each side of the stand. Said catch a is shown as a 65 plate mounted over a recess cut in the edge of the piece to which it is secured, which permits said latch to pass toward the center of the structure when the receptacle is tilted. A bar B' extends longitudinally of said receptacle, being secured to its ends in its center at its top, and has downwardly-extending partitions B² hinged to its opposite sides, which partitions are held apart at their lower edges by means of a spring b², interposed between them and so arranged as to normally 70 force them apart. A spring-wire frame B³, of the form shown in Fig. 3, is also mounted on the outer face of each of said partitions and is adapted to press the sheets against the 75 sides of the receptacle, thus holding them smooth and straight. Extending up from the top of the central bar B' is a pin (one or more, as preferred) b³, adapted to strike the inner face of the side rail of the table-frame 80 when the receptacle is tilted to one side or other and limit its movement, as shown in 85 Figs. 1 and 4.

In Fig. 4, in lieu of the partitions B², I have shown two spring-wire frames or partitions 90 of a form similar to the frame B³, as shown in Fig. 3, which, as will be readily understood, will operate in the same manner as do the partitions shown in Fig. 2, provided with the springs, although not being of a form calculated to hold the music or other articles so 95 firmly in place.

In operation the sheets are placed in the receptacle between the sides thereof and the spring-partitions, where they are securely 100 clamped and pressed together and held in a flat and smooth condition at all times. When ac-

cess is desired to one side or the other of the portfolio, the spring-latch b' of the side to be used is released from the catch a and the receptacle tilted on its pivots until the stop b^3 strikes the side piece of the table, which thus holds the receptacle in the position most convenient for access. When the receptacle is tilted in one direction, the latch b' on the opposite side passes through the recess in the side piece beneath the catch a , as before described. The sheets being slid in under the springs, the lower edges of the partitions are forced tightly against the lower edges of the sheets and the spring-frames on the sides of the partitions press firmly against the sides of the sheets. By this construction, as will be readily seen, many sheets or only a few are held in place in the receptacle in the same manner and with equal firmness.

As will be readily understood, the operation of the construction shown in Fig. 4 is substantially the same as that shown in the other figures of the drawings and could be used without departing from my invention, as could other modifications of the form shown in Fig. 2 which will readily suggest themselves, my invention consisting, broadly speaking, in providing the stand with the swinging receptacle having the spring-mounted parts arranged to clamp and hold the sheets therein, substantially as described.

Having thus fully described my said invention, what I claim as new, and desire to secure by Letters Patent, is—

1. The combination, in a portfolio, of a stand having a closed top, end supports or legs therefor, a receptacle consisting of a unitary structure pivoted between said end supports on pivots located centrally between its sides, where-

by said receptacle can be swung out in either 40 direction, the sides of said receptacles being arranged to register with the under side of the top structure when in its closed position, and stops for limiting the outward movement of said receptacle, all substantially as set forth. 45

2. The combination, in a portfolio, of the stand, the receptacle pivoted between its ends and beneath its top and formed with a central bar extending longitudinally of its top, partitions or frames hinged to the sides thereof and extending to near the bottom of said receptacle, the spring interposed between said partitions near their lower edges and adapted to force them apart, and another spring secured to the outer surface of each of said partitions and adapted to press outwardly against the sheets placed between them and the sides of said receptacle, substantially as set forth. 55

3. The combination, in a portfolio, of the stand, the receptacle pivoted beneath the top 60 thereof, the sides of which are arranged to register with the under side of said top when in its closed position, provided with the central bar, the spring-actuated frames or partitions extending down from said bar, catches secured to the sides of said receptacle and arranged to engage with the side pieces of said stand, and stops for limiting the movement of said receptacle, located thereon intermediate of its sides, substantially as set forth. 70

In witness whereof I have hereunto set my hand and seal, at Indianapolis, Indiana, this 12th day of March, A. D. 1891.

CHAS. N. LEONARD. [L. S.]
